UNITED STATES PATENT OFFICE.

EBERHARD FABER, OF NEW YORK, N. Y.

DESIGN FOR A RULER.

SPECIFICATION forming part of Design No. 35,254, dated November 5, 1901.

Application filed March 28, 1901. Serial No. 53,363. Term of patent 14 years.

To all whom it may concern:

Be it known that I, EBERHARD FABER, a citizen of the United States of America, and a resident of the city of New York, in the State of New York, have invented and produced a new, useful, and original Design for a Ruler, of which the following is a specification, reference being had to the accompanying sheet of drawings, forming part thereof.

Figure 1 is a perspective view of a ruler, showing my new design; and Fig. 2 is an end view of the same.

As shown in the drawings, the leading or material features of my design consist of a peculiarly-curved top *a*, the surface of which extends in an unbroken flat curve from a sharp front edge *b* in the plane of a flat bot-

tom *c* to the top of a back edge *d*, and the ogee shape of said back edge, whereby when the ruler is viewed from either end a pleasing combination of curves is formed by said top and back edge, as in Fig. 2.

Having described my said design, what I claim as my invention, and desire to patent under this specification, is—

The design for a ruler, substantially as herein shown and described.

In testimony whereof I have signed my name to this specification in the presence of two subscribing witnesses.

EBERHARD FABER.

Witnesses:

EDWARD E. HUBER,
WM. S. EBBETS.
